UNITED STATES PATENT OFFICE.

MAX HERSKOVITZ, OF CHICAGO, ILLINOIS.

DESIGN FOR A LAMP-CHIMNEY FOR INCANDESCENT GAS-LIGHTS.

SPECIFICATION forming part of Design No. 30,367, dated March 21, 1899.

Application filed December 10, 1898. Serial No. 698,920. Term of patent 3½ years.

To all whom it may concern:

Be it known that I, MAX HERSKOVITZ, a citizen of the United States, residing at Chicago, in the county of Cook and State of Illinois, have invented and produced a new and original Design for Lamp-Chimneys for Incandescent Gas-Lights, of which the following is a specification, reference being had to the accompanying drawings, forming a part thereof.

Figure 1 is a perspective view of a chimney, showing my new design. Fig. 2 is a vertical sectional view showing the general features thereof.

The leading characteristic features of my design are found in the unitary article made the subject of illustration, consisting of a cylindrical body of glass A, having an astragal bead E one-third of the distance from the top

down. Half an inch above the bead the body is reduced in diameter a half-inch, leaving a shoulder in the form of an ogee curve C. The remaining portion extending upward is left plain. The body below the bead is finished plain downward to within a half-inch of the bottom, where it is slightly curved outward.

Having described my invention, what I claim as new, and wish to secure by Letters Patent, is—

The design for a lamp-chimney for incandescent gas-lights, as herein described and shown.

MAX HERSKOVITZ.
